UNITED STATES PATENT OFFICE.

BRUNO RAETTIG, OF HOFFNUNGSTHAL, NEAR COLOGNE, GERMANY.

PLUG SWITCH.

Application filed December 27, 1922. Serial No. 609,355.

To all whom it may concern:

Be it known, that I, BRUNO RAETTIG, a citizen of the German Republic, residing at Hoffnungsthal, near Cologne, Germany, have **5** invented certain new and useful Improvements in Plug Switches, of which the following is a specification.

This invention relates to a plug switch in which the one contact part is an oscillating switch member.

The known devices of this type are of very complicated construction; they require rather large openings in the casing whereby the water and dust tightness of the casing **15** is impaired. The manipulation of the known devices is difficult, specially with the large sized devices. As in the devices of known construction the hand of the operator remains in contact with the plug and the **20** succession of the insertion of plug and switching in is not all ensured, the operator is not absolutely protected from electric shocks.

The invention has for its object to obviate **25** these inconveniences.

According to the invention the plug which carries the second contact part has slits for the reception of the oscillating switch member, which may be made of several parts for **30** instance of several knife switches and which in the working position of the plug, is hidden and covered in the box. In the switching off position it has been swung back into the box casing so that it is well protected **35** against accidental contact.

In order to increase the security against accidental contact of current conducting parts the oscillating switch member is preferably bent in angle shape, especially in **40** U-shape towards its fulcrum.

The oscillating-switch member can be connected with a cam disk, the cams of which serve, the one for securing in the switch in position when the plug is in its inserted **45** position, and the other for the locking of the device if the plug is withdrawn.

The locking of the plug in the inserted position is preferably effected by a pusher pressed against the lid by means of the cam **50** so that a nose of the lid is held in engagement with a nose of the plug. A bolt can serve for locking the switch; this bolt engages with a groove arranged in the wall which surrounds the plug hole. The bolt is **55** oscillated at the insertion of the plug by the action of a lateral projection of this plug

against the action of a spring so that it moves out of the path of the switch cam and so that the bolt releases the cam if the plug is inserted, the operation of the switch being **60** thus possible. If the plug is withdrawn the bolt prevents the operation of the switch. In this manner the switching-in is prevented if the plug is withdrawn and the withdrawal of the plug at the switched in position of **65** the switch is prevented whereby the safety of the device is considerably increased.

On the drawing several forms of construction of the device according to this invention are shown by way of example.

Fig. 1 shows the preferred form of construction in vertical longitudinal section.

Fig. 2 is a front elevation of Fig. 1.

Fig. 3 shows a second form of construction in vertical longitudinal section.

Fig. 4 shows the essential parts of a third form of construction in longitudinal section.

Fig. 5 is a plan view of Fig. 4.

Fig. 6 shows a fourth form of construction which is similar to that shown in Fig. 3 but comprises special devices for preventing the withdrawal of the plug if the switch is switched in and the switching-in of the switch if the plug is withdrawn.

Fig. 7 shows in end elevation the plug used in the form of construction Fig. 6.

Fig. 8 shows a longitudinal section through a part of the device on a larger scale and it illustrates the arrangement of the locking bolt used in the device shown in Fig. 6 together with the cam of the switch.

Fig. 9 is a cross section perpendicular to Fig. 8. In the Figs. 8 and 9 the locking bolt is in the locking position.

Fig. 10 is a section similar to Fig. 9, the bolt being shown in the releasing position.

Figs. 11 and 12 are elevations corresponding to Figs. 9 and 10 respectively.

In the form of construction shown in Figs. 1 and 2 the switch knife *a* and the contact spring *b* which serves at the same time as pivot axle for the switch knife are arranged upon an insulated base plate *c* of the casing *d* of the switch box. The corresponding contact spring *e* of the switch is arranged upon the insulation *f* for the plug in the plug casing *g*.

The switch knife *a* is operated in the well known manner by a lever *h* upon the outer side of the casing. A bow *i* connected with the lever *h*, gets in the switching-in position in front of the opening of the box and

prevents thus the insertion of the plug *g* or, the plug *g* being inserted, the withdrawal of the same.

If the plug *g* has to be withdrawn the lever *h* has to be brought to the position indicated by dash- and dot lines. The bow *i* is oscillated also 90° and the switch knife *a* is brought out of engagement with the contact springs *e*. At the switching-off movement the switch knife *a* moves out of the plug insulator through the slot *k*.

When the switch has been brought into a switching off position the plug *g* may be pulled out of casing *d*.

The plug insulation *f* is box-shaped so that the contacts *e* are protected by said insulation. The number of the plug contacts *e*, of the knives *a* and of the slots *k* corresponds with the number of poles of the switch.

At the bottom end of the opening of casing *g* for the insertion of the plug a plate *l* with slots *m* is arranged which protects the parts in the casing.

In the form of construction Fig. 3 the switch knife *a* is bent in U-shape and mounted between the contact springs *b* by the end of one of its arms. The contact springs are thus situated above the contact springs of the inserted plug.

Upon the pivot axle of the switch knives the bows *n* are pivotally mounted which are connected the one with the other by the insulating plate *o*. The switch knives *a* are connected with the bows *n* by springs not shown on the drawing. Upon the pivot axle of the switch knives *a* and of the bows *n* there is further arranged a lever *p* which is rigidly fixed upon the pivot axle. The end of the lever is fork-shaped and embraces the end of rail *q* mounted upon the insulating plate *o*. If lever *p* is oscillated by the aid of the switch lever arranged upon the outer side of the casing *d*, it draws first along the bows and, as soon as the springs arranged between the bows *n* and the switch knives *a* are sufficiently tensioned the switch knives *a* will be pulled out from between the contact springs *e*.

The insulating plate *l* obturates in this case the plug space of the casing *d* with the exception of the small slots *m* arranged in the insulating plate which permit the passage of the switch knives through the plate *l*. The switch knives *a* get, owing to their U-shape and the special mounting completely out of the range of the slots *m*, they stand above these slots so that even an intentional touching of the current conducting switch knives through the slots *m* is prevented. Owing to the narrowness of the slots the interior of the casing is better protected against dust and other impurities than in the form of construction shown in Figs. 1 and 2.

In the second form of construction the plug insulation is perfectly protected by the plug mantle whilst it projects at the top from the plug mantle in the form of construction shown in Figs. 1 and 2.

The form of construction shown in Figs. 4 and 5 will be used particularly if instantaneous switching is not required which is the case with arrangements limited by space, for instance in line couplings.

In this form of construction the switching in and out of the plug contacts is effected by the forward and backward movement of the switch knives *a*. The current carrying is effected by sliding contacts *r*.

In the form of construction shown in Figs. 6-12 the casing *d* is composed of the bottom part 1 and of the top part 2. In the removable top part 2 all the operative parts are arranged. The bottom part 1 comprises only an insulating partition 3 designed to prevent a contact of the ends of the leads with the current carrying parts.

Upon the axle 4 the switch knives *a* are pivotally mounted in a similar manner as in Fig. 3. The current is led in by springs *b*. Springs *o* connect the switch knives *a* with the bows *n*, these latter being connected with one another by the insulating plate *o*. Upon this plate the catch rail *q* is fixed the end of which is embraced by the fork-shaped end of lever *p* which is rigidly connected with the axle 4.

This axle 4 carries further the switch lever *h* and a cam disk 6 which as shown in the drawing is made in one piece with the fork-shaped lever *p*. The cam disk 6 has a cam 7 which, when the switch is being brought to the switching in position, acts upon a pin 8 movably arranged in part 2 of the casing so that the end of this pin 8 projects from the casing and acts upon the nose *q* of lid 10 which covers the inlet opening of the switch if the plug is withdrawn.

The lid 10 is pressed downward so that the nose 11 of the lid cannot be removed from the path of nose 12 of plug *g* even by an upwardly directed pressure upon the lid. The inserted plug is consequently secured against withdrawal.

A second cam 13 of cam disk 6 co-operates with a bolt 14 which is pivotally mounted upon the bolt 16 but acted upon by a torsion spring 15. An extension 17 of the bolt engages with a groove 18 which is arranged in the wall of the plug hole of the casing.

As long as the bolt is in the position shown in Figs. 9 and 11 the bolt 14 obstructs the path of cam 13 so that the switch cannot be turned.

The plug *g* has a laterally projecting nose 19 which is guided in the groove 18 of the insertion of the plug. In the end position of the plug the nose 19 pushes the extension 17 of bolt 14 out of the groove and makes

the bolt 14 oscillate from the position Figs. 9 and 11 into the position Figs. 10 and 12, so that the cam 13 can freely pass along the bolt 14 so that the switch knives can be oscillated.

When the plug *g* is being withdrawn from the switch the torsion spring 15 brings the bolt 14 back to the position shown in Fig. 9 so that the switch is secured in the 10 switching off position. The operation of the structure illustrated in Figs. 6 to 12 inclusive may be briefly described as follows. When the plug *g* has been inserted and the lever *h* moved to switching position the cam 15 disc 6 will be swung about its pivot to cause the cam surface 7 to displace the pin 8 in an outward direction whereupon it engages the nose 9 formed on the lid 10. Obviously, this lid has been previously raised to permit 15 the insertion of the plug *g*. The pressure of the pin 8 upon the nose 9 causes the nose 11 of the cover 10 to engage the nose 12 formed on the plug *g* and maintains the nose 11 in the path of the nose 12 to prevent 20 the withdrawal of the plug *g* while the switch lever *h* is in its "on" position.

A projection 17 on a rotatably mounted bolt 14 is adapted to extend into a groove 18 arranged in the wall of the casing 30 through which the plug *g* is inserted. The plug *g* is provided with a nose 19 which, upon the insertion of the plug is adapted to engage the extension 17 of the bolt 14 and to rotate the same against the action of a 35 spring 15, thus moving the bolt 14 out of the path of a cam 13 formed on the cam disc 16. Obviously before the plug *g* has been inserted to remove the bolt 14 from the path of the cam 13, the switch lever *h* cannot 40 be moved in the switching position. Therefore the switch is secured in "off" position until the insertion of the plug *g*.

I claim:—

1. An improved plug switch in which the 45 alive contact member is constructed as an oscillatable switch member comprising in combination, a box, an angularly shaped switch member oscillatably mounted in said box, the box being formed with slots through 50 which said switch member passes from the "off" into the "on" position, said angular switch member being moved in the "off" position away from said slots and a plug carrying another contact part adapted to engage with said switch member.

2. An improved plug switch in which the alive contact member is constructed as an oscillatable switch member comprising in combination a switch box, a switch member 60 oscillatably mounted in said box in a manner to be protected therein in the "off" position, a plug, another contact part upon said plug adapted to engage directly with said oscillatable switch member, means for locking the plug in its inserted position

when the switch is in "on" position and separate means including a rotatable bolt for locking the switch in "off" position if the plug is withdrawn.

3. An improved plug switch in which the 70 alive contact member is constructed as an oscillating switch member comprising in combination a switch box, the switch member oscillatively mounted in said box in a manner that it is protected therein in the off position, a plug, another contact part upon said plug, a switch lever pivotally mounted in said switch box, a cam disk upon the inner end of the said switch lever, two cams on said disk, means cooperating with one 75 of said cams for locking the plug in the inserted position, and a separate locking bolt controlled by said plug and cooperating with the other cam if the plug is withdrawn, for locking said lever. 80

4. An improved plug switch in which the alive contact member is constructed as an oscillating switch member comprising in combination a switch box, the switch member oscillatively mounted in said box in a manner that it is protected therein in the off position, a plug, another contact part upon said plug, a nose laterally projecting from said plug, a switch lever pivotally mounted in said switch box, a cam disk upon the inner end of said switch lever, two cams of said disk on which one is designed to lock the plug in the inserted position, an abutment face on the lid of the switch box, a nose on 90 said lid, a pin movably arranged in the switch box and adapted to be pressed against said abutment face by the action of said other cam of the cam disk so that said nose of the lid engages with the nose of the plug. 95

5. An improved plug switch in which the alive contact member is constructed like an oscillating switch member comprising in combination a switch box, the switch member oscillatively mounted in said box in a manner that it is protected therein in the off position, a plug, another contact part upon said plug, a switch lever pivotally mounted in said switch box, a cam disk upon the inner end of said switch lever, two cams of said disk on which one is designed to lock the plug in the inserted position, a cylindrical guide for the plug in said switch box having a guide groove in its wall, a locking bolt located in the switch box so that it projects into said guide groove, a spring which holds said locking bolt into the path of said other cam and a lateral extension of the plug designed to act upon the inner end of said locking bolt to swing the same, against the action of said spring, out of the path of 100 said cam. 105

The foregoing specification signed at Cologne, Germany, this 24th day of November, 1922.

BRUNO RAETTIG.
